(57) **CLAIM**

The ornamental design for a massaging apparatus for legs, as shown and described.

DESCRIPTION

FIG. 1 is a front view of a massaging apparatus for legs according to one embodiment of the present invention, shown with air bags in a deflated configuration.

FIG. 2 is a rear view of the massaging apparatus for legs of FIG. 1, shown with air bags in a deflated configuration.

FIG. 3 is a top view of the massaging apparatus for legs of FIG. 1, shown with air bags in a deflated configuration.

FIG. 4 is a bottom view of the massaging apparatus for legs of FIG. 1, shown with air bags in a deflated configuration.

FIG. 5 is a left side view of the massaging apparatus for legs of FIG. 1, shown with air bags in a deflated configuration.

FIG. 6 is a right side view of the massaging apparatus for legs of FIG. 1, shown with air bags in a deflated configuration.

FIG. 7 is a perspective view of the massaging apparatus for legs of FIG. 1, shown with air bags in a deflated configuration.

FIG. 8 is a front view of the massaging apparatus for legs of FIG. 1, shown with air bags in an inflated configuration.

FIG. 9 is a rear view of the massaging apparatus for legs of FIG. 1, shown with air bags in an inflated configuration.

FIG. 10 is a top view of the massaging apparatus for legs of FIG. 1, shown with air bags in an inflated configuration.

FIG. 11 is a bottom view of the massaging apparatus for legs of FIG. 1, shown with air bags in an inflated configuration.

FIG. 12 is a left side view of the massaging apparatus for legs of FIG. 1, shown with air bags in an inflated configuration.

FIG. 13 is a right side view of the massaging apparatus for legs of FIG. 1, shown with air bags in an inflated configuration.

FIG. 14 is a perspective view of the massaging apparatus for legs of FIG. 1, shown with air bags in an inflated configuration; and,

FIG. 15 is a right side view of the massaging apparatus for legs of FIG. 1, shown with a movable table of the apparatus in an angled configuration.
